STEEL HARDENING AND TEMPERING MACHINE.

1,183,809.

Specification of Letters Patent.

Patented May 16, 1916.

Application filed October 15, 1906. Serial No. 339,112.

To all whom it may concern:

Be it known that we, FRANKLIN S. FRISBEE and MALCOLM H. BAKER, citizens of the United States, and residents of Boston, in the county of Suffolk and State of Massachusetts, have invented certain new and useful Improvements in Steel Hardening and Tempering Machines, of which the following is a specification.

10 In hardening and tempering thin, flat steel articles, the chief difficulties encountered have been uneven heating, or overheating and burning of the steel, distortion or buckling when placed in the cooling and 15 hardening medium, and an uncertain degree of evenness of hardening and tempering. It has usually been the custom to heat such steel between heated metal blocks, under pressure, and to cool and harden the same 20 between chilled blocks, also under pressure. This was to insure a flat and even article, and was superior to hardening in a liquid medium, since the latter, by touching the steel at one point first, as the steel was 25 placed in the medium, resulted in distortion. To effect the transfer from the heating to the cooling blocks usually required mechanical contact with the steel, and resulted in uneven structure. In tempering, the steel 30 was usually heated to the proper degree by observing the color of the scale of the oxid formed, and this process required considerable skill and watchfulness, since the least departure from the correct degree of heating produced either a too brittle or a too 35 soft article.

It is the object of the invention to provide a means for hardening and tempering steel, especially thin, flat steel articles, automatically and homogeneously, which enables the steel to pass successively from a conveyer to heating, cooling and tempering mediums continuously and with uniformity.

A further object is to avoid the possibility 45 of overheating and burning, or of underheating and softening the steel.

A further object is to harden the steel homogeneously and perfectly flat and with no distortion or buckling.

50 A further object is to temper the hardened steel to the correct degree, and with no necessity of watchfulness and skill, or dependence upon the color of the oxid formation.

A further object is to harden and temper

the steel without the employment of mechanical contact, or a carrier, in passing from the heating through the cooling and tempering mediums. 55

A further object is to carry the steel through the operation described automatically and continuously, in order that a large number of articles may be easily and economically handled. 60

A further object is to provide a machine of durable qualities, particularly in the heating portions, of the heating blocks. 65

A further object is to provide means for accurately and quickly noting and governing the temperatures of the heating blocks, the cooling blocks, and the tempering chamber. 70

In carrying out our invention we employ two heating blocks of a highly heat conductive material maintained at a uniform and predetermined temperature, in order to assure the even distribution of heat, and a consequent even heating of the steel, and we face these blocks with a highly infusible and non-oxidizing metal at the faces in contact with the steel to assure durability and 75 smooth wear of the faces. 80

In order to maintain the cooling blocks at the desired temperature, and to prevent their heating from the heated steel, we provide the blocks with water jacketed backings, and face them with a highly heat conductive material which rapidly carries away the heat of the steel to the water, and thus prevents a rise in the temperature of the blocks, and assures a rapid cooling and perfect 90 hardening of the steel. Water jacketed chambers may be placed, if desired, above the cooling heads and tempering chamber, so as to keep the heat in the heating heads and tempering chamber away from the cooling heads, as much as possible. In order to secure even, accurate, and uniform tempering of the steel, we place the steel, at this stage, in a chamber provided with a heating plate heated from a heated metal tube, of 95 heat conductive material, the heating plate and the metal tube being maintained at a uniform and predetermined temperature. 100

In order to avoid mechanical carrying of the steel from one stage to the next, we employ electro-magnets to hold and center the steel between the heating blocks and in the tempering chamber, and we cause the heated 105

steel to fall by gravity from the heating blocks to the cooling blocks, and thence to the tempering chamber. And further, to assure the proper closing of the heating and 5 cooling blocks, and the proper retention of the steel within the tempering chamber, we operate the motion of the blocks by electro-magnets, the energizing of the magnets being properly timed.

10 In order to render the entire action automatic, we convey the steel to the heating blocks by a system of electro-magnetic control, and we govern the entire action of the electro-magnets by a rotating commutator, 15 which actuates the electro-magnets in the proper manner and at the proper intervals to assure a continuous passage of steel articles through the machine.

In order to govern the temperature of the 20 heating blocks, and of the tempering chamber, we place a thermostat upon the blocks and a thermometer within the chamber, and heat the blocks and chamber by means of a gas flame, which is easily and accurately 25 regulated, or by a gas air blast.

In order to avoid too sudden heating of the steel, we arrange the parts of the machine so that the steel is subjected to a gradually increasing heat as it passes through 30 the electro-magnetic receptacle or conveyer to the heating blocks.

We do not limit our invention to any precise position, arrangement or number of magnets or burners in operating the machine, but may use such as best carry out 35 the purpose of the invention, and we do not restrict our invention to the use of any specific sources of heat or cold in operating the heating heads, cooling heads, tempering 40 chamber, and cooling means under the tempering chamber since any suitable forms may be used.

We have illustrated our invention in the annexed drawings, in which—

45 Figure 1 is a side elevation and Fig. 2 a plan view of our improved hardening and tempering machine. Fig. 3 is an end view of the machine and Fig. 4 is a detail view of the commutator device governing the 50 electro-magnets, together with the electrical connections.

In the drawings, 1 and 2 are heating heads formed of solid copper and faced with faces 12, 12 preferably of platinum or other 55 suitable metal. These heads carry lugs 3, 3, 3, 3, through which pass rods 4, 4. The head 1 is permanently attached to the base plate 16 by a bracket 5, and the head 2 is attached to the rods 4, 4. These rods pass through 60 guide brackets 6, 6, located behind the head 2 and attached to the plate 16, and carry heads 7, 7. Coiled springs 8, 8, located between the heads and the brackets 6, 6, cause the rods 4, 4, to separate the heating 65 heads 1, 2. At the other end of the rods

4, 4, is attached the armature 11 of an electro-magnet 13 so that when the magnet is energized the armature is attracted and the heads 1, 2, are closed firmly.

An electro-magnet 64 constantly energized or a permanent magnet is mounted between the arms of the magnet 13, and is attached to the back of the magnet, so that it sets up a constant magnetic field adapted to magnetically arrest and hold a steel article 70 against and within the area of the face 12 of the heating head 1 and to substantially center it upon the face 12 of the heating head 1. Gas burners, consisting of gas tubes 61, 61, and air tubes 62, 62, are mounted in 75 an upright post 14, which post also supports the magnet 13. These burners heat the heads 1 and 2, without interference with the magnets 13 and 64. The head 2 is heated by a single burner consisting of a gas 80 tube 58 and an air tube 59, supported in a bracket 60 attached to the upright post 23 set upon the base 16. The heating heads are sufficiently large to entirely inclose the steel article while being heated and they thereby 85 protect it from direct contact with the air and consequent oxidization of the steel.

The steel articles to be hardened and tempered, shown in this particular instance as thin, flat, uniform steel blanks, are placed in 90 a receptacle or conveyer 17, composed of brass or copper, or other non-magnetic material, by means of an opening 19 in the top of the receptacle. This receptacle 17 is attached to the iron core of an electro-magnet 100 21, the wire of the magnet appearing at 22, and the core being mounted in the post 23. The receptacle 17 also carries, in the end 105 opposite to the opening 19, an opening 18, of a width sufficient to permit the passage 110 of one of the steel articles at a time, and provided, if desired, with means for varying the size of the opening, so as to permit the passage of articles of various sizes. This 115 opening 18 is so located that steel passing through it falls directly down between the heating heads 1, 2. The electro-magnetic field set up by the magnet 21 attracts the 120 steel article nearest the magnet and draws it to the end of the receptacle over the opening 18. This steel article in turn attracts the next one, and in this manner the magnetism is transmitted throughout the entire line of steel articles contained within the receptacle, drawing them all over toward the magnet 21. When the current flowing 125 through the wire 22 is interrupted, the magnetic field ceases, and the single steel article over the opening 18 falls through the opening and down between the heating heads 1, 2, where it is magnetically arrested, held 130 against and within the area of the face 12 of the heating head 1 by the magnet 64 and substantially centered upon and in contact with the face 12 of the heating head 1 by 135

the magnetic force of the magnet 64, the heating heads being closed and held firmly by the action of the electro-magnet 13, after the steel article has been arrested and held 5 against the face 12 of the heating head 1 by the magnet 64. When the steel article is heated to the temperature of the heads, the circuit through the magnet 13 is interrupted, the heads separate through the action of the 10 spring 8, and the steel article, being now heated to a degree at which it is magnetically inert, is no longer held in position by the magnet 64 but falls away from the heating heads, through an opening 28 in the 15 base 16.

In order to make and break the circuit through the magnet wire 22 of the magnet 21, we place a contact point 9 upon the head 7 of one of the rods 4, and attach an 20 upright spring strip 10 to the base 16 carrying a second contact point 66 adapted to engage with the point 9 when the heads 1, 2, are separated, and to disengage from the point when the heads come together. By this arrangement a new steel blank is drawn into 25 position over the opening 18 in the receptacle 17, whenever the heads are brought together, and is freed to fall down between the heads whenever they are separated, thus 30 rendering the passing of the steel blanks to the heads automatic, it being only necessary to keep a sufficient number of blanks in the receptacle.

The base 16 is composed of some non-heat 35 conducting material, such as fire clay, to prevent the downward transmission of heat, and carries posts 56, 56, 56, 56, attached to the base by nuts 57, 57, 57, 57, these posts extending down to a second base 43. On 40 this base is mounted a hollow head 31 by means of a bracket 39, and a second hollow head 67 is carried by rods 35, 35, which pass through guide pieces 34, 34, attached to the head 31 and also through brackets 68, 68, 45 set upon the base 43. These rods also carry heads 37, 37, and springs 36, 36, which are adapted to separate and maintain open the heads, when the magnet is deenergized. An 50 electro-magnet 40 is mounted on the base 43, which operates to close the heads 31, 37 when energized by attracting the armature 38. In order to maintain the heads 31, 67, at the proper cooling temperature, the faces 33, 33, are composed preferably of silver or 55 copper, these metals being of the highest heat conductivity, and are provided with inlet and outlet tubes 70, 71, 72, 73, whereby a continuous passage of cold water may be maintained behind the faces.

60 Posts 59, 59, 59, 59, pass from the base 43 to a base 67 below, upon which is mounted a bracket 54 carrying a horizontal copper tube 51. This tube is expanded at one end into a hollow chamber 49, open at the front and having a heating plate 50 at its

base in contact with the expanded end of the tube 51, and adapted to receive the steel article as it falls through an opening 69 in the base 43, the steel article being magnetically arrested, held against and within 70 the area of the heating plate 50 and substantially centered upon and in contact with the face of the heating plate 50 in the chamber by the magnetic force of an electro-magnet 52, extending through the tube 51, and 75 wound on the portion outside of the tube with wire 53 carrying an electric current. A Bunsen burner 74 is mounted upon the base 57, which heats the tube 51 and thereby the chamber at the head of the tube. The 80 burner 74, may as desired, be placed above or below the magnet 52. The degree of heat within this chamber is noted upon a thermometer 55 set in a bracket 75. An opening 76 in the base of the chamber permits the 85 passage of the steel article from the chamber when the circuit of the magnet 52 is interrupted, and an opening in the base 57 allows the steel article to fall through the base and into a receptacle 78 containing a 90 cooling liquid, the receptacle appearing at 75 and resting upon a foundation base 79, the foundation base supporting the entire superstructure by means of posts 60, 60, 60, 60.

The commutator 80 is mounted upon the 95 base 81 by supports 82, 82, and is operated by a belt 84 driven by any suitable means, such as a motor, or clockwork. This commutator carries three separate faces of varying diameter, 85, 86, 87, covered with facing 100 strips of metal 88, 89, 90. Metal brushes 91, 92, 93, are supported in a post 94 by means of insulating strips 95, 96, 97, and bear against the faces 85, 86, 87, as the commutator revolves. These brushes are suitably connected to the electro-magnets 13, 105 40, and 52, and also to a source of electrical supply 98, so that the magnets are energized at the proper intervals to render the passage of steel articles through the machine automatic, when the commutator is 110 revolved at the correct speed.

In order to partially heat the steel articles before they reach the heating blocks, and thereby improve the quality of the 115 hardened steel articles, we compose the receptacle or conveyer 17 of copper, or other good heat conductor, and thus cause the receptacle to absorb sufficient heat from the gas burners to gradually heat the steel articles as they pass through it.

In Fig. 4, showing the details of the commutator, and the electrical connections, the source of electrical supply appears at 98, and the shaft upon which the commutator 120 revolves at 99.

The operation of our improved steel hardening and tempering machine is as follows:—When the receptacle 17 is filled with steel articles and the electrical connections 130

established, the electro-magnet 21 draws the steel articles over toward the opening 18, and upon the interruption of the circuit in the magnet 21 a single steel article falls down between the heads 1, 2, where it is caught and centered by the magnet 64. The revolution of the commutator then energizes the magnet 13 and the heads are closed, gripping the steel article firmly, heating and flattening it. The heads 1, 2, next open and the heated steel article, which is now magnetically inert, falls down through the opening 28 and is mechanically caught and held by the closing of the cooling heads 31, 67, where it is suddenly cooled. The cooling heads then separate, and the hardened steel article falls through the opening 69 and down to the open end of the chamber in the copper tube 51, into which it is drawn and held on the heating plate 50 by the action of the magnet 52. This magnet retains the steel article in the chamber until it is heated to the proper tempering heat, when the magnet 52 is deenergized, and the steel article, now tempered properly, falls through the opening 76 into the receptacle 78. The steel articles are delivered successively to the heating heads 1 and 2 by means of the opening and closing of the electrical circuit through the magnet 21, which is controlled by the opening and closing of the heating heads 1 and 2 and the consequent making and breaking of the circuit by the contact points 9 and 66. It may be desirable for some steel articles to use a tempering bath instead of the tempering chamber 51, in which case the electro-magnet 52 operating the tempering chamber may be disconnected by an electrical switch or other suitable means, and a tempering bath placed in the receptacle 78, then the steel article passing from the cooling heads 31, 67, under the influence of gravity will pass directly through the tempering chamber 51 into the receptacle 78. In like manner, if so desired, the receptacle 17 and the electro-magnet 21 may be disconnected from electrical connection with the commutator and steel articles may then be fed by hand or otherwise directly into the heads 1, 2.

The entire apparatus may be inclosed in a muffle or the heating heads and the tempering chamber only, if so desired, as is commonly done in apparatus for hardening and tempering steel.

The degree of heat of the heating heads may be noted by any suitable thermostatic device attached to the heads, and the proper heat obtained by regulating the intensity of the gas burners.

The various magnets used in connection with the receptacle, heating heads and tempering chamber may be water cooled, if desired.

65 The proper timing of the passage of steel

articles through the machine, and the proper intervals of their retention in the various heating and cooling mediums, is regulated by the speed of the commutator, and the relative lengths and positions of the contact strips 88, 89, 90.

The operation of the commutator is as follows:—The brush 91 first makes contact with the strip 88, closing the circuit through the magnet 13, and thus closing the heating heads 1, 2, upon a steel article, the steel article having descended from the receptacle 17. The brush 92 next leaves the strip 89, breaking the circuit of the magnet 40 and allowing the cooling heads to open. The brush 93 next leaves the strip 90, opening the circuit of the tempering chamber magnet 52. As the revolution continues, the brush 91 leaves the strip 88, opening the heads 1, 2, and allowing the heated steel article to fall down between the cooling heads, where it is caught by the closing of the heads, which is caused by the brush 92 making contact with the strip 89. The interval between the opening of the heating heads and the closing of the cooling heads is accurately timed, as indicated by the angular distance between the dotted lines 100, 101, so that the steel article is accurately gripped between the cooling heads. As the revolution of the commutator continues, the brush 92 leaves the strip 89, the cooling heads open, and the steel article falls, and is caught and centered by the magnet 52, which has been energized by the making of the contact between the brush 93 and the strip 90. The steel article is thereby held within the tempering chamber until the contact breaks, when it falls into the receptacle 78. In the meantime the circuit through the magnet 21 has been broken by the separation of the contact points 9, 66, and a new steel article has fallen down between the heating heads. The intervals of action of the various magnets governed by the commutator are indicated by the angular distances between the dotted lines 100, 101, 102, in Fig. 4. By this method the speed, time of heating and cooling, and the feeding of the steel articles to the machine, is accomplished with mathematical precision by the adjustment of the elements,—speed of commutator, length and position of contact strips, and adjustment of contact brushes, and it is only necessary to watch the thermometers indicating the degree of heat of the heating heads, the thermometer showing the heat of the tempering chamber, and to keep the receptacle supplied with steel articles.

Our object in facing the heating heads 125 preferably with platinum is because this metal does not oxidize at the high temperature used. We do not limit our invention, however, to the use of platinum faces on the heating heads, nor to the use of silver faces 130

on the cooling heads, but prefer using platinum and silver, because they are the metals best adapted for the particular use in each case and give the best results. Our object 5 in facing the cooling heads with silver or copper is to rapidly carry away to the water the heat of the steel articles. Silver is particularly adapted for this purpose since it is highest in heat conductivity. It is needful to cool the heated steel articles as rapidly 10 as possible in order to secure the best hardened product.

We claim as our invention:—

1. In a machine for automatically hardening and tempering steel, magnetic means 15 adapted to cause the steel to move from one end to the other of the receptacle, heating heads, cooling heads and a tempering chamber, electromagnetic means for operating the 20 said receptacle, means adapted to open and normally hold apart the said heating heads and cooling heads, means adapted to close the said heating heads and cooling heads, magnetic means adapted to arrest and hold 25 the steel by magnetic force in contact with the heating heads and tempering medium until every portion of the steel is heated to a predetermined temperature, means for producing these mediums, and means adapted 30 to permit the steel to fall to and from the said heating heads, cooling heads and tempering chamber.

2. In a machine for automatically hardening and tempering steel, heating heads 35 composed of a highly heat conductive material, cooling heads composed of a highly heat conductive material, means for maintaining a circulation of cool liquid through the said cooling heads, means adapted to 40 open and normally hold apart the said heating heads and cooling heads, means adapted to close the said heating heads and cooling heads, and magnetic means adapted to arrest and hold the steel by magnetic force in 45 contact with the heating heads until every portion of the steel is heated to a predetermined temperature.

3. In a machine for automatically hardening and tempering steel, a receptacle to 50 contain the said steel, heating heads, cooling heads, a tempering chamber, magnetic means adapted to arrest and hold the steel by magnetic force in contact with the heating heads and tempering medium until 55 every portion of the steel is heated to a predetermined temperature, means adapted to permit the steel to fall to and from the said heating heads, cooling heads and tempering chamber, and heating and cooling means 60 for producing the heating, cooling and tempering mediums.

4. In a machine for automatically hardening and tempering steel, a receptacle to

contain steel articles, heating heads, cooling heads, a tempering chamber, magnetic 65 means adapted to cause the steel articles to move from one end to the other of the receptacle, means to permit the steel articles to fall to and from the said heating heads, cooling heads and tempering chamber, magnetic 70 means adapted to arrest and hold the steel articles by magnetic force automatically and successively in the said heating heads and tempering chamber until every portion of the steel articles is heated to a 75 predetermined temperature, means for heating the heating heads and tempering chamber, and means for cooling the cooling heads.

5. In a machine for automatically hardening and tempering steel, a receptacle to 80 contain steel articles, heating heads, cooling heads, a tempering chamber, magnetic means adapted to cause the steel articles to move from one end to the other of the receptacle, means adapted to permit the steel articles to fall to and from the said heating heads, cooling heads and tempering chamber, means for heating the said heads, magnetic means adapted to arrest and hold the 85 steel in contact with the heating heads until every portion of the steel is heated to a predetermined temperature, cooling heads, means adapted to permit the steel articles to fall to and from the said heating heads, cooling heads and tempering chamber, means for cooling the said heads, a tempering chamber, magnetic means adapted to arrest and hold the steel in contact with a heated 90 tempering medium in the tempering chamber until every portion of the steel is heated to a predetermined temperature, means for heating the said tempering medium in the said tempering chamber, means adapted to open and normally hold apart the said heating heads and cooling heads, and means 95 adapted to close the said heating heads and cooling heads.

6. In a machine for automatically hardening and tempering steel, a receptacle for 100 holding a quantity of the steel articles to be hardened and tempered, heating heads of a highly conductive material, means for heating the said heads, magnetic means adapted to arrest and hold the steel by magnetic force in contact with the said heating heads until every portion of the steel is heated to a predetermined temperature and the steel thereby adapted to be homogeneously hardened, means for relatively moving the said heating heads, cooling heads composed of a highly heat conductive material, means for cooling the said heads, means for relatively moving the said heads, a tempering chamber, magnetic means adapted to 115 arrest and hold the steel by magnetic force 120

125

in the tempering chamber in contact with a heated body until every portion is heated to a predetermined temperature, means for heating the said chamber, a cooling medium, 5 and means adapted to permit the steel articles to fall to and from the said heating heads, cooling heads and tempering chamber.

7. In a machine for automatically hardening and tempering steel, a receptacle to 10 contain steel articles, an electro-magnet located at one end of the said receptacle, a slot in the base of the said receptacle and adapted to cause the steel articles to move from one end to the other of the receptacle, 15 this slot being located at the end of the receptacle which carries the electro-magnet, and also being of a width sufficient to permit the passage of a single steel article, heating heads composed of a highly heat conductive material, magnetic means adapted to arrest and hold the steel by magnetic force in contact with the said heating heads until every portion of the steel is heated to a predetermined temperature and the steel there- 20 by adapted to be homogeneously hardened, means for opening the said heating heads, means for relatively closing the said heating heads, a contact make and break device operated by the motion of the said heads, 25 and governing the energizing of the electro-magnet of the holding receptacle, cooling heads consisting of chambers carrying a continuous supply of a cooling liquid and composed of a highly heat conductive material, 30 means for opening the said cooling heads, means for relatively closing the said cooling heads, a tempering chamber composed of a highly heat conductive material, magnetic means adapted to arrest and hold 35 the steel by magnetic force in the tempering chamber in contact with a heated body until every portion of the steel is heated to a predetermined temperature, a cooling medium, 40 and a source of electrical supply connected to the various electro-magnets through a suitable commutator in such a manner as to render the passage of the steel through 45 the machine automatic.

40 8. In a machine for automatically hardening and tempering steel, heating heads composed of a highly heat conductive material, cooling heads composed of a highly heat conductive material, means for maintaining a circulation of cool liquid through the said cooling heads, means for opening and closing the said heating heads relatively, and 45 means for opening and closing the said cooling heads relatively.

50 9. In a machine for automatically hardening and tempering steel, a heated recep-

65 tacle, means for gradually heating the steel in the said receptacle from a point of minimum to a suitable point of maximum heat, means for causing the said steel to move through the said receptacle and to be released therefrom, heating heads composed of a highly heat conductive material, means 70 for heating the said heads, cooling heads composed of a highly heat conductive material, means for cooling the said heads, a tempering chamber, a heated tube for conducting the heat to the said tempering chamber, and means for heating the said tube.

75 10. In a machine for automatically hardening and tempering steel, heating surfaces, cooling surfaces and a heating chamber, means for heating the said surfaces, 80 means for separating the said surfaces, means for closing the said surfaces upon the steel, magnetic means adapted to arrest and hold the steel by magnetic force in contact with the said heating surfaces until every 85 portion of the steel is heated to a predetermined temperature, means for cooling the said surfaces, means for separating the said surfaces upon the steel, a heating chamber, means 90 for heating the said heating chamber, magnetic means adapted to arrest and hold the steel by magnetic force in the tempering chamber in contact with a heated body until every portion of the steel is heated to a predetermined temperature, a cooling medium, 95 and a source of electrical supply connected to the various electro-magnets through a suitable commutator in such a manner as to render the passage of the steel through 100 the machine automatic.

105 11. In a machine for automatically hardening and tempering steel, a receptacle to contain the said steel, heating heads, cooling heads, magnetic means adapted to cause the 110 steel to move from one end to the other of the receptacle, means adapted to open the said heating heads and cooling heads, magnetic means adapted to close the said heating heads and cooling heads, magnetic 115 means adapted to arrest and hold the steel by magnetic force in contact with the said heating heads until every portion of the steel is heated to a predetermined temperature, a tempering chamber, magnetic means adapted to arrest and hold the steel by magnetic force in the tempering chamber in contact with a heated body until every portion of the steel is heated to a predetermined temperature, means adapted to permit the steel 120 to fall from the receptacle to and from the said heating heads, cooling heads and tempering chamber, and a commutator, so connected to the various electro-magnets controlling and operating in connection with 125 the said receptacle, heating heads, cooling

- heads and tempering chamber, together with means for heating the said heating heads and tempering chamber and cooling the said cooling heads, and to a source of electrical supply, as to render automatic the operation of the machine.
12. In a machine for automatically hardening and tempering steel, heating heads and a tempering chamber, and magnetic means adapted to arrest and hold the steel by magnetic force in contact with the heating heads and a heated body in the tempering chamber until every portion of the steel is heated to a predetermined temperature.
13. In a machine for automatically hardening and tempering steel, heating heads, cooling heads, a tempering chamber, means adapted to open the said heating heads and cooling heads, means adapted to close the said heating heads and cooling heads, and magnetic means adapted to arrest and hold the steel by magnetic force in contact with the heating heads and a heated body in the tempering chamber until every portion of the steel is heated to a predetermined temperature.
14. In a machine for automatically hardening and tempering steel, heating heads, cooling heads, a tempering chamber, magnetic means adapted to arrest and hold the steel by magnetic force in contact with the said heating heads until every portion of the steel is heated to a predetermined temperature, a heated body in the said tempering chamber, magnetic means adapted to arrest and hold the steel by magnetic force in the tempering chamber in contact with the said heated body until every portion of the steel is heated to a predetermined temperature.
15. In a machine for automatically hardening and tempering steel, heating heads, cooling heads, a tempering chamber, magnetic means adapted to cause the steel to move from one end to the other of a receptacle, means adapted to permit the steel to fall to and from the said heating heads, cooling heads and tempering chamber, and magnetic means adapted to arrest and hold the steel by magnetic force in contact with the said heating heads and tempering medium until every portion of the steel is heated to a predetermined temperature.
16. In a machine for automatically hardening and tempering steel, a receptacle to contain the said steel, an electro-magnet located at one end of the said receptacle and adapted to cause the steel to move from one end to the other of the receptacle, heating heads and cooling heads, magnetic means adapted to arrest and hold the steel by magnetic force in contact with the said heating heads until every portion of the steel is heated to a predetermined temperature, a tempering chamber, magnetic means adapted to arrest and hold the steel by magnetic force in contact with the heating heads and tempering chamber in contact with a heated body until every portion of the steel is heated to a predetermined temperature, means for heating the said heating heads and tempering chamber, means for cooling the said cooling heads, and a commutator, so connected to the various electro-magnets controlling and operating in connection with the said receptacle, heating heads, cooling heads and tempering chamber, and to a source of electrical supply, as to render automatic the operation of the machine.
17. In a machine for automatically hardening and tempering steel, a receptacle to contain the said steel, an electro-magnet located at one end of the said receptacle and adapted to cause the steel to move from one end to the other of the receptacle, heating heads, cooling heads, a tempering chamber, means adapted to open and normally hold apart the said heating heads and cooling heads, magnetic means adapted to close the said heating heads and cooling heads, magnetic means adapted to arrest and hold the steel by magnetic force in contact with the said heating heads until every portion of the steel is heated to a predetermined temperature, means adapted to permit the steel to fall from the receptacle to and from the said heating heads, cooling heads and tempering chamber, and an electrical rotating commutator, together with means for operating the said commutator, so connected to the said electro-magnets operating in connection with the receptacle, heating heads, cooling heads and tempering chamber, and to a source of electrical supply, as to render automatic the operation of the machine.
18. In a machine for automatically hardening and tempering steel, a receptacle to contain the said steel, an electro-magnet located at one end of the said receptacle and adapted to cause the steel to move from one end to the other of the receptacle, an opening in the base of said receptacle adjacent to the electro-magnet, heating heads, cooling heads and a tempering chamber, means adapted to open and normally hold apart the said heating heads and cooling heads, magnetic means adapted to close the said heating heads and cooling heads, magnetic means adapted to arrest and hold the steel by magnetic force in contact with the said heating heads until every portion of the steel is heated to a predetermined temperature, means adapted to permit the steel to fall from the receptacle to and from the said heating heads, cooling heads and tempering chamber, means for heating the said heating heads and tempering chamber and cooling the said cooling heads, and a commutator, so connected to the electro-magnets operating in connection with the said receptacle, heating heads, cooling heads and tempering chamber, and to a source of electrical supply, as to render automatic the operation of the machine.

tempering chamber, and to a source of electrical supply, as to render automatic the operation of the machine.

19. In a machine for automatically hardening and tempering steel, a receptacle to contain the said steel provided with an electro-magnet located at one end of the said receptacle, and adapted to cause the steel to move from one end to the other of the receptacle, an opening in the base of said receptacle adjacent to the electro-magnet, means for varying the size of said opening, heating heads, cooling heads, and a tempering chamber, means adapted to open and normally hold apart the said heating heads and cooling heads, magnetic means adapted to close the said heating heads and cooling heads, magnetic means adapted to arrest and hold the steel by magnetic force in contact with the said heating heads until every portion of the steel is heated to a predetermined temperature, means adapted to arrest and hold the steel by magnetic force in the tempering chamber in contact with a heated body until every portion of the steel is heated to a predetermined temperature, means adapted to permit the steel to fall from the receptacle to and from the said heating heads, cooling heads and tempering chamber, means for heating the said heating heads and tempering chamber and cooling the said cooling heads, and a commutator, together with means for adjusting the said commutator, so connected to the various electro-magnets controlling and operating in connection with the said receptacle, heating heads, cooling heads and tempering chamber, and to a source of electrical supply, as to render automatic the operation of the machine.

20. In a machine for automatically hardening and tempering steel, a receptacle to contain the said steel, magnetic means adapted to cause the steel to move from one end to the other of the receptacle, heating heads, cooling heads and tempering chamber, magnetic means adapted to arrest and hold the steel by magnetic force in contact with the said heating heads until every portion of the steel is heated to a predetermined temperature, electrical means for operating the said electro-magnets of the said receptacle, heating heads, cooling heads and tempering chamber, means adapted to permit the steel to fall from the receptacle to and from the said heating heads, cooling heads and tempering chamber, means for heating the said heating heads and tempering chamber and cooling the said cooling heads, means for cooling the said electro-magnets operating the receptacle, heating heads and tempering chamber, and a commutator, together with means for adjusting the said commutator, so connected to the various electro-magnets controlling and operating in connection with the said receptacle, heating heads, cooling heads and tempering chamber, and to a source of electrical supply, as to render automatic the operation of the machine.

21. In a machine for automatically har-

dening and tempering steel, a receptacle to contain the said steel, an electro-magnet located at one end of the said receptacle and adapted to cause the steel to move from one end to the other of the receptacle, heating heads and cooling heads, means adapted to open and normally hold apart the said heating heads and cooling heads, magnetic means adapted to close the said heating heads and cooling heads, electro-magnetic means adapted to arrest and hold the steel by magnetic force in contact with the said heating heads until every portion of the steel is heated to a predetermined temperature, a tempering chamber, electro-magnetic means adapted to arrest and hold the steel by magnetic force in the tempering chamber in contact with a heated body until every portion of the steel is heated to a predetermined temperature, means adapted to permit the steel to fall from the receptacle to and from the said heating heads, cooling heads and tempering chamber, means for heating the said heating heads and tempering chamber, means for cooling the said cooling heads, means for determining and regulating the temperature of the heating heads and the tempering chamber, and a commutator, so connected to the various electro-magnets controlling and operating in connection with the said receptacle, heating heads, cooling heads and tempering chamber, and to a source of electrical supply, as to render automatic the operation of the machine.

22. In a machine for automatically hardening and tempering steel, a receptacle to contain the said steel provided with an electro-magnet located at one end of the said receptacle and adapted to cause the steel to move through the receptacle and to be released therefrom, an opening in the base of said receptacle adjacent to the electro-magnet, means for varying the size of said opening, heating heads, cooling heads and a tempering chamber, means adapted to open and normally hold apart the said heating heads and cooling heads, magnetic means adapted to close the said heating heads and cooling heads, electro-magnetic means adapted to arrest and hold the steel by magnetic force in contact with the said heating heads until every portion of the steel is heated to a predetermined temperature, means adapted to permit the steel to fall from the receptacle to and from the said heating heads, cooling heads and tempering chamber, means for heating the said heating heads and tempering chamber and cooling the said cooling heads, means for determining and regulating the temperature of the heating heads and the tempering chamber, electro-magnetic means adapted to arrest and hold the steel by magnetic force in the tempering chamber in contact with a heated body until

every portion of the steel is heated to a predetermined temperature, and a commutator, together with means for adjusting the said commutator, so connected to the various electro-magnets controlling and operating in connection with the said receptacle, heating heads, cooling heads and tempering chamber, and to a source of electrical supply, as to render automatic the operation of the machine.

23. In tempering apparatus, a heater having a metal-blank conducting passage therethrough, means to arrest temporarily a metal-blank article within the passage, and means to raise the temperature of the heater exterior to the passage.

24. The method of hardening thin steel blanks, consisting in raising the steel blanks to a predetermined high temperature by conduction from heated bodies maintained at the desired temperature, holding the steel blanks by magnetic force in contact with the said heated bodies until every portion of the said blanks is heated to a predetermined temperature, and then chilling them.

25. The method of hardening thin steel blanks, consisting in raising the steel blanks to the necessary high temperature by conduction from previously-heated solid bodies maintained at a substantially uniform temperature, holding the steel blanks by magnetic force in contact with the said previously-heated bodies until every portion of the said blanks is heated to a predetermined temperature, and then chilling them by conduction from solid bodies of sufficient mass as to be substantially unaffected in temperature by contact with the blanks being treated.

40 26. The method of hardening thin steel blanks, consisting in raising the steel blanks to a moderately high temperature, subsequently raising them to a higher temperature by means of conduction from a previously-heated solid body, holding the steel blanks by magnetic force in contact with the said previously-heated body until every portion of the said blanks is heated to a predetermined temperature, and then chilling them.

45 27. The method of hardening thin steel blanks, consisting in raising them to a moderately high temperature, subsequently raising them to a higher temperature by conduction from a previously-heated solid conductor, holding the steel blanks by magnetic force in contact with the said previously-heated solid conductor until every portion of the said blanks is heated to a predetermined temperature, and then chilling them.

60 28. The method of hardening thin steel blanks, consisting in raising them to a moderately high temperature, subsequently confining them, raising them to a higher temperature, and holding them by magnetic

force when so confined until every portion of the said blanks is heated to a predetermined temperature, and then chilling them.

29. The method of hardening thin steel blanks, consisting in raising them to a moderately high temperature, subsequently confining them, raising them to a higher temperature, and holding them by magnetic force when so confined until every portion of the said blanks is heated to a predetermined temperature, and then chilling them while confined under pressure.

30. The method of hardening thin steel blanks, consisting in heating them to a predetermined temperature by means of a previously-heated solid body, holding the steel blanks in contact with the said previously-heated body until every portion of the said blanks is heated to a predetermined temperature, and then chilling them by contact with cold surfaces between which they are held stationary under pressure upon substantially their entire surfaces.

31. The method of hardening thin steel blanks, consisting in raising them to a high temperature by means of a previously-heated solid conductor, holding the steel blanks by magnetic force in contact with the said previously-heated solid conductor until every portion is heated to a predetermined temperature, and then chilling them while stationary by conduction from a cold body.

32. The method of hardening thin steel blanks, consisting in heating them by means of a previously heated solid conductor, holding the steel blanks by magnetic force in contact with the said previously-heated solid conductor until every portion is heated to a predetermined temperature, and then chilling them while stationary by contact with a cold metal surface.

33. The method of hardening thin steel blanks, consisting in raising them to a high temperature by contact with a previously-heated solid conductor, holding the steel blanks by magnetic force in contact with the said previously-heated solid conductor until every portion is heated to a predetermined temperature, and then chilling them between cold surfaces.

34. The method of hardening thin steel blanks, consisting in raising them to a predetermined temperature by contact with a previously-heated solid conductor, holding the steel blanks by magnetic force in contact with the said previously-heated solid conductor until every portion is heated to a predetermined temperature, subjecting them to a blow with a cold metal piece, and chilling them by contact with the said metal piece.

35. The method of hardening thin steel blanks, consisting in heating them by contact between previously-heated solid surfaces, holding the steel blanks by magnetic

- force in contact with the said previously-heated solid surfaces until every portion of the said blanks is heated to a predetermined temperature, and then chilling them.
- 5 36. The method of hardening steel blanks, consisting in raising the steel blanks to a moderately high temperature, subsequently confining them between suitable hot surfaces, holding the steel blanks by magnetic force 65
10 in contact with the said hot surfaces until every portion of the said blanks is heated to a predetermined temperature, and subjecting them to the action of a blow and chilling them.
- 15 37. The method of hardening steel blanks, consisting in raising them to a moderately high temperature, subsequently confining them between suitable hot surfaces, holding the steel blanks by magnetic force in contact with the said hot surfaces until every portion of the said blanks is heated to a predetermined temperature, and chilling them. 70
20
- 25 38. The method of hardening thin steel blanks, consisting in raising them to a moderately high temperature, subsequently confining them between suitable hot surfaces, holding the steel blanks by magnetic force in contact with the said hot surfaces until every portion of the said blanks is heated to a predetermined temperature, and chilling them between cold surfaces. 75
30
- 35 39. The method of hardening thin steel blanks, consisting in heating the steel blanks by conduction from a previously-heated solid body maintained at a substantially uniform temperature, holding the steel blanks by magnetic force in contact with the said previously-heated solid body until every portion of the said blanks is heated to a predetermined temperature, and chilling them. 80
40
- 45 40. The method of hardening thin steel blanks, consisting in heating the steel blanks by contact with a previously-heated solid conductor, holding the steel blanks by magnetic force in contact with the said previously-heated solid conductor until every portion of the said blanks is heated to a predetermined temperature, and then chilling them 85
50 while held stationary under pressure between cold surfaces maintained at a substantially uniform temperature. 90
- 55 41. The method of hardening thin steel blanks, consisting in heating and chilling the steel blanks by conduction from solid metallic bodies each of which is maintained at a substantially uniform temperature necessary to effect the heating and chilling operations, and holding the steel blanks by magnetic force in contact with the said heated, solid metallic bodies until every portion of the said blanks is heated to a predetermined temperature. 95
60
42. The method of hardening thin steel blanks, consisting in heating and chilling the blanks by conduction from solid metallic bodies of such size or mass as to be substantially unaffected in temperature by contact with the blanks being treated, and holding the steel blanks by magnetic force in contact with the said heated, solid metallic bodies until every portion of the said blanks is heated to a predetermined temperature. 100
65
43. The method of manufacturing steel blanks, consisting in stamping the blanks from unhardened sheet metal, heating them to the necessary hardening temperature by means of a previously-heated solid conductor, holding the steel blanks by magnetic force in contact with the said previously-heated solid conductor until every portion of the said blanks is heated to a predetermined temperature, and chilling them while held stationary under pressure between cold surfaces. 105
70
44. The method of manufacturing steel blanks, consisting in stamping the blanks from soft sheet metal, heating them by conduction from heated, solid metallic bodies, holding the steel blanks by magnetic force in contact with the said heated, solid metallic bodies until every portion of the said blanks is heated to a predetermined temperature, and chilling them between cold surfaces. 110
75
45. The method of hardening thin steel blanks, consisting in heating them by conduction from previously-heated solid bodies maintained at a substantially uniform temperature, holding the steel blanks by magnetic force in contact with the said previously-heated bodies until every portion of the said blanks is heated to a predetermined temperature, and then chilling them by contact with metal bodies maintained at the necessary low temperature. 115
80
46. The method of hardening thin steel blanks, consisting in confining the steel blanks and raising them to the necessary high temperature by conduction from and confining them by previously-heated solid bodies maintained at a substantially uniform high temperature, holding the steel blanks by magnetic force in contact with the said previously-heated solid bodies until every portion of the said blanks is heated to a predetermined temperature, and then chilling them by confinement by and contact with solid bodies maintained at the necessary low temperature. 120
